Primary Examiner — Cynthia Underwood(74) *Attorney, Agent, or Firm* — Lucem, PC; Heedong Chae(57) **CLAIM**

The ornamental design for a container for a coil hose, as shown and described.

DESCRIPTION

FIG. 1 is a front perspective view of a container for a coil hose showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another front perspective view thereof; and,

FIG. 10 is a front perspective view of the container shown in use with the coil hose.

The broken line showing of environment is for illustrative purposes only and forms no part of the claimed design.
